ABSTRACT

A crank operated long tape measure includes a reel member and a casing side member having an internal center post with a conical free end. The reel member has a central shaft extending toward the center post for engagement therewith, the central shaft being axially segmented to define a plurality of leg portions. The free ends of the segmented leg portions bear against the conical end of the center post to assure centering of the reel within the casing while simultaneously providing constant frictional engagement between the reel member and the casing for resisting rotary movement of the reel member with respect to the casing. A long tape blade is secured to the reel for storage within the casing. The blade is provided with a laterally weakened break area adjacent its butt end and a replacement tape attaching aperture intermediate the break area and the butt end. Both the break area and the attaching aperture are spaced from the butt end by a distance sufficient to permit full exposure thereof outside the casing without disengagement of the butt end from the reel.

TAPE MEASURE

BACKGROUND AND SUMMARY OF THE INVENTION

The present invention relates generally to measuring tapes and is more particularly concerned with a crank operated tape measure having a relatively long rule blade.

It is an object of the present invention to provide a new and improved crank operated long tape of economical construction that resists unintentional unwinding or rewinding of the blade. Included in this object is the provision for a reel that coacts directly with the casing to provide the dual function of automatically centering the reel within the casing and of providing constant frictional engagement to prevent free-wheeling of the reel and facilitate the application of a smooth torque force when rewinding the tape blade.

Another object of the present invention is to provide a new and improved measuring tape of the type described including a tape blade construction that permits replacement of the blade without opening the casing. Included in this object is the provision for an explicable attachment means adjacent the innermost or butt end of the blade that permits removal of a damaged or worn blade and replacement with a new blade without disassembly of the casing.

Still another object of the present invention is to provide a new and improved tape measure of the type described that is particularly well suited for long tapes having a length of about 50 feet, 100 feet or more wherein the casing is provided with snap-fit interlocking elements capable of rapid initial assembly and of holding the casing in its assembled condition until it is permanently secured. Included in this object is the provision for a tape measure having fixedly secured mating casing parts and a tape blade with an integral "leader" portion that permits replacement of the blade in a simple and facile manner without disrupting the securely assembled casing.

A still further object of the present invention is to provide a manually operated long tape measure of economical yet rugged and durable construction that is well suited to rapid assembly.

Other objects will be in part obvious and in part pointed out in more detail hereinafter.

These and related objects are accomplished in accordance with the present invention by providing a tape measure comprising a casing, a reel member mounted on the casing for rotary motion relative thereto, and a relatively long tape wound within the casing and having one end extending outwardly therefrom. The casing is provided with a short center post and the reel member includes a central shaft extending toward the center post for engagement therewith. The central shaft is segmented to define a plurality of leg portions having free ends bearing against the center post to thereby assure centering of the reel within the casing while simultaneously providing constant frictional engagement between the reel member and the casing for resisting rotary motion of the reel member with respect to the reel casing.

A better understanding of the invention will be obtained from the following detailed description and the accompanying drawing which set forth an illustrative

embodiment indicative of the way in which the principles of the invention are employed.

A BRIEF DESCRIPTION OF THE DRAWING

5 In the drawing:

FIG. 1 is an elevational view, partially broken away, of a tape measure embodying the features of the present invention, the tape blade being illustrated in a fully extended position;

10 FIG. 2 is an enlarged bottom view, partially broken away and partially in section, of the tape measure of FIG. 1 detailing portions of the reel member;

FIG. 3 is a further enlarged end view of the central shaft of the reel member of FIG. 2; and,

15 FIG. 4 is a top view of the exposed terminal portion of the blade of FIG. 1.

DESCRIPTION OF A PREFERRED EMBODIMENT

Referring now to the drawing in greater detail 20 wherein like reference numerals indicate like parts throughout the several figures, the tape measure 10 of the present invention is illustrated as being comprised of a casing consisting of a pair of mating casing side members 12, 14 which, in their assembled condition, 25 define an enclosed tape storage cavity 16. An opening 18 in one end wall of the casing provides communication with the storage cavity 16 and permits withdrawal and retraction of a long tape blade 20 such as a metal blade of about 50 or 100 feet in length. The mating side members 12, 14 are provided with side walls 22, 24 respectively having slightly concave exterior surfaces at the central portions thereof. The side member 14 is free of openings except to provide for passage of the blade 20 into and out of cavity 16 while side member 12 has an enlarged circular central aperture 28 in its side wall 22 with a radially extending lip 30 defining its periphery. The interior surface of side wall 24 is provided with a center post 32 projecting for a short distance into the interior of the casing and terminating in a conically shaped nose 34 on the free end thereof. The casing side members 12, 14 are constructed of a suitably durable material. In the preferred embodiment, high impact polystyrene has been found to give excellent results and similar tough molded plastics may be used.

25 A circular reel or hub member 38 is positioned within the large central aperture 28 and is provided with a peripheral flange 40 that cooperates with the lip 30 of the casing to prevent withdrawal of the reel from the casing. The reel projects outwardly from the side wall 22 and is provided with a transverse slot 42 well suited for storing a crank arm 44. The reel 38 is further provided with a generally cylindrical integrally depending skirt-like drum 46 that integrally extends across the interior 50 of the casing and is received within a circular groove 48 within the side member 14, the groove 48 circumscribing center post 32 and being spaced therefrom by a radial distance less than the radius of aperture 28. The drum 46 defines an interior wall of storage cavity 16 and is provided with an appropriate key-hole slot 50 to permit secured attachment thereto of the T-shaped interior or butt end 52 of the tape blade 20. The crank arm 44 of reel 38 is provided with a projecting handle 54 adjacent one end and its opposite end is pivotably 55 mounted within slot 42 through a snap fit connection on pin 56 for movement between the closed or stored position illustrated in FIG. 1 and the open operating 60 position illustrated in FIG. 2. The handle 54 is provided with a stop 58 which limits the extent of movement of the handle 54 and the reel 38. The reel 38 is provided with a shoulder 62 which defines a shoulder 64 which is received within a shoulder 66 of the side member 14. The shoulder 62 is provided with a shoulder 68 which defines a shoulder 70 which is received within a shoulder 72 of the side member 12. The shoulder 68 is provided with a shoulder 74 which defines a shoulder 76 which is received within a shoulder 78 of the side member 14. The shoulder 74 is provided with a shoulder 80 which defines a shoulder 82 which is received within a shoulder 84 of the side member 12. The shoulder 80 is provided with a shoulder 86 which defines a shoulder 88 which is received within a shoulder 90 of the side member 14. The shoulder 86 is provided with a shoulder 92 which defines a shoulder 94 which is received within a shoulder 96 of the side member 12. The shoulder 92 is provided with a shoulder 98 which defines a shoulder 100 which is received within a shoulder 102 of the side member 14. The shoulder 98 is provided with a shoulder 104 which defines a shoulder 106 which is received within a shoulder 108 of the side member 12. The shoulder 104 is provided with a shoulder 110 which defines a shoulder 112 which is received within a shoulder 114 of the side member 14. The shoulder 110 is provided with a shoulder 116 which defines a shoulder 118 which is received within a shoulder 120 of the side member 12. The shoulder 116 is provided with a shoulder 122 which defines a shoulder 124 which is received within a shoulder 126 of the side member 14. The shoulder 122 is provided with a shoulder 128 which defines a shoulder 130 which is received within a shoulder 132 of the side member 12. The shoulder 128 is provided with a shoulder 134 which defines a shoulder 136 which is received within a shoulder 138 of the side member 14. The shoulder 134 is provided with a shoulder 140 which defines a shoulder 142 which is received within a shoulder 144 of the side member 12. The shoulder 140 is provided with a shoulder 146 which defines a shoulder 148 which is received within a shoulder 150 of the side member 14. The shoulder 146 is provided with a shoulder 152 which defines a shoulder 154 which is received within a shoulder 156 of the side member 12. The shoulder 152 is provided with a shoulder 158 which defines a shoulder 160 which is received within a shoulder 162 of the side member 14. The shoulder 158 is provided with a shoulder 164 which defines a shoulder 166 which is received within a shoulder 168 of the side member 12. The shoulder 164 is provided with a shoulder 170 which defines a shoulder 172 which is received within a shoulder 174 of the side member 14. The shoulder 170 is provided with a shoulder 176 which defines a shoulder 178 which is received within a shoulder 180 of the side member 12. The shoulder 176 is provided with a shoulder 182 which defines a shoulder 184 which is received within a shoulder 186 of the side member 14. The shoulder 182 is provided with a shoulder 188 which defines a shoulder 190 which is received within a shoulder 192 of the side member 12. The shoulder 188 is provided with a shoulder 194 which defines a shoulder 196 which is received within a shoulder 198 of the side member 14. The shoulder 194 is provided with a shoulder 200 which defines a shoulder 202 which is received within a shoulder 204 of the side member 12. The shoulder 200 is provided with a shoulder 206 which defines a shoulder 208 which is received within a shoulder 210 of the side member 14. The shoulder 206 is provided with a shoulder 212 which defines a shoulder 214 which is received within a shoulder 216 of the side member 12. The shoulder 212 is provided with a shoulder 218 which defines a shoulder 220 which is received within a shoulder 222 of the side member 14. The shoulder 218 is provided with a shoulder 224 which defines a shoulder 226 which is received within a shoulder 228 of the side member 12. The shoulder 224 is provided with a shoulder 230 which defines a shoulder 232 which is received within a shoulder 234 of the side member 14. The shoulder 230 is provided with a shoulder 236 which defines a shoulder 238 which is received within a shoulder 240 of the side member 12. The shoulder 236 is provided with a shoulder 242 which defines a shoulder 244 which is received within a shoulder 246 of the side member 14. The shoulder 242 is provided with a shoulder 248 which defines a shoulder 250 which is received within a shoulder 252 of the side member 12. The shoulder 248 is provided with a shoulder 254 which defines a shoulder 256 which is received within a shoulder 258 of the side member 14. The shoulder 254 is provided with a shoulder 260 which defines a shoulder 262 which is received within a shoulder 264 of the side member 12. The shoulder 260 is provided with a shoulder 266 which defines a shoulder 268 which is received within a shoulder 270 of the side member 14. The shoulder 266 is provided with a shoulder 272 which defines a shoulder 274 which is received within a shoulder 276 of the side member 12. The shoulder 272 is provided with a shoulder 278 which defines a shoulder 280 which is received within a shoulder 282 of the side member 14. The shoulder 278 is provided with a shoulder 284 which defines a shoulder 286 which is received within a shoulder 288 of the side member 12. The shoulder 284 is provided with a shoulder 290 which defines a shoulder 292 which is received within a shoulder 294 of the side member 14. The shoulder 290 is provided with a shoulder 296 which defines a shoulder 298 which is received within a shoulder 300 of the side member 12. The shoulder 296 is provided with a shoulder 302 which defines a shoulder 304 which is received within a shoulder 306 of the side member 14. The shoulder 302 is provided with a shoulder 308 which defines a shoulder 310 which is received within a shoulder 312 of the side member 12. The shoulder 308 is provided with a shoulder 314 which defines a shoulder 316 which is received within a shoulder 318 of the side member 14. The shoulder 314 is provided with a shoulder 320 which defines a shoulder 322 which is received within a shoulder 324 of the side member 12. The shoulder 320 is provided with a shoulder 326 which defines a shoulder 328 which is received within a shoulder 330 of the side member 14. The shoulder 326 is provided with a shoulder 332 which defines a shoulder 334 which is received within a shoulder 336 of the side member 12. The shoulder 332 is provided with a shoulder 338 which defines a shoulder 340 which is received within a shoulder 342 of the side member 14. The shoulder 338 is provided with a shoulder 344 which defines a shoulder 346 which is received within a shoulder 348 of the side member 12. The shoulder 344 is provided with a shoulder 350 which defines a shoulder 352 which is received within a shoulder 354 of the side member 14. The shoulder 350 is provided with a shoulder 356 which defines a shoulder 358 which is received within a shoulder 360 of the side member 12. The shoulder 356 is provided with a shoulder 362 which defines a shoulder 364 which is received within a shoulder 366 of the side member 14. The shoulder 362 is provided with a shoulder 368 which defines a shoulder 370 which is received within a shoulder 372 of the side member 12. The shoulder 368 is provided with a shoulder 374 which defines a shoulder 376 which is received within a shoulder 378 of the side member 14. The shoulder 374 is provided with a shoulder 380 which defines a shoulder 382 which is received within a shoulder 384 of the side member 12. The shoulder 380 is provided with a shoulder 386 which defines a shoulder 388 which is received within a shoulder 390 of the side member 14. The shoulder 386 is provided with a shoulder 392 which defines a shoulder 394 which is received within a shoulder 396 of the side member 12. The shoulder 392 is provided with a shoulder 398 which defines a shoulder 400 which is received within a shoulder 402 of the side member 14. The shoulder 398 is provided with a shoulder 404 which defines a shoulder 406 which is received within a shoulder 408 of the side member 12. The shoulder 404 is provided with a shoulder 410 which defines a shoulder 412 which is received within a shoulder 414 of the side member 14. The shoulder 410 is provided with a shoulder 416 which defines a shoulder 418 which is received within a shoulder 420 of the side member 12. The shoulder 416 is provided with a shoulder 422 which defines a shoulder 424 which is received within a shoulder 426 of the side member 14. The shoulder 422 is provided with a shoulder 428 which defines a shoulder 430 which is received within a shoulder 432 of the side member 12. The shoulder 428 is provided with a shoulder 434 which defines a shoulder 436 which is received within a shoulder 438 of the side member 14. The shoulder 434 is provided with a shoulder 440 which defines a shoulder 442 which is received within a shoulder 444 of the side member 12. The shoulder 440 is provided with a shoulder 446 which defines a shoulder 448 which is received within a shoulder 450 of the side member 14. The shoulder 446 is provided with a shoulder 452 which defines a shoulder 454 which is received within a shoulder 456 of the side member 12. The shoulder 452 is provided with a shoulder 458 which defines a shoulder 460 which is received within a shoulder 462 of the side member 14. The shoulder 458 is provided with a shoulder 464 which defines a shoulder 466 which is received within a shoulder 468 of the side member 12. The shoulder 464 is provided with a shoulder 470 which defines a shoulder 472 which is received within a shoulder 474 of the side member 14. The shoulder 470 is provided with a shoulder 476 which defines a shoulder 478 which is received within a shoulder 480 of the side member 12. The shoulder 476 is provided with a shoulder 482 which defines a shoulder 484 which is received within a shoulder 486 of the side member 14. The shoulder 482 is provided with a shoulder 490 which defines a shoulder 492 which is received within a shoulder 494 of the side member 12. The shoulder 490 is provided with a shoulder 496 which defines a shoulder 498 which is received within a shoulder 500 of the side member 14. The shoulder 496 is provided with a shoulder 502 which defines a shoulder 504 which is received within a shoulder 506 of the side member 12. The shoulder 502 is provided with a shoulder 508 which defines a shoulder 510 which is received within a shoulder 512 of the side member 14. The shoulder 508 is provided with a shoulder 514 which defines a shoulder 516 which is received within a shoulder 518 of the side member 12. The shoulder 514 is provided with a shoulder 520 which defines a shoulder 522 which is received within a shoulder 524 of the side member 14. The shoulder 520 is provided with a shoulder 526 which defines a shoulder 528 which is received within a shoulder 530 of the side member 12. The shoulder 526 is provided with a shoulder 532 which defines a shoulder 534 which is received within a shoulder 536 of the side member 14. The shoulder 532 is provided with a shoulder 540 which defines a shoulder 542 which is received within a shoulder 544 of the side member 12. The shoulder 540 is provided with a shoulder 546 which defines a shoulder 548 which is received within a shoulder 550 of the side member 14. The shoulder 546 is provided with a shoulder 552 which defines a shoulder 554 which is received within a shoulder 556 of the side member 12. The shoulder 552 is provided with a shoulder 560 which defines a shoulder 562 which is received within a shoulder 564 of the side member 14. The shoulder 560 is provided with a shoulder 566 which defines a shoulder 568 which is received within a shoulder 570 of the side member 12. The shoulder 566 is provided with a shoulder 572 which defines a shoulder 574 which is received within a shoulder 576 of the side member 14. The shoulder 572 is provided with a shoulder 580 which defines a shoulder 582 which is received within a shoulder 584 of the side member 12. The shoulder 580 is provided with a shoulder 586 which defines a shoulder 588 which is received within a shoulder 590 of the side member 14. The shoulder 586 is provided with a shoulder 592 which defines a shoulder 594 which is received within a shoulder 596 of the side member 12. The shoulder 592 is provided with a shoulder 598 which defines a shoulder 600 which is received within a shoulder 602 of the side member 14. The shoulder 598 is provided with a shoulder 604 which defines a shoulder 606 which is received within a shoulder 608 of the side member 12. The shoulder 604 is provided with a shoulder 610 which defines a shoulder 612 which is received within a shoulder 614 of the side member 14. The shoulder 610 is provided with a shoulder 616 which defines a shoulder 618 which is received within a shoulder 620 of the side member 12. The shoulder 616 is provided with a shoulder 622 which defines a shoulder 624 which is received within a shoulder 626 of the side member 14. The shoulder 622 is provided with a shoulder 630 which defines a shoulder 632 which is received within a shoulder 634 of the side member 12. The shoulder 630 is provided with a shoulder 636 which defines a shoulder 638 which is received within a shoulder 640 of the side member 14. The shoulder 636 is provided with a shoulder 642 which defines a shoulder 644 which is received within a shoulder 646 of the side member 12. The shoulder 642 is provided with a shoulder 650 which defines a shoulder 652 which is received within a shoulder 654 of the side member 14. The shoulder 650 is provided with a shoulder 656 which defines a shoulder 658 which is received within a shoulder 660 of the side member 12. The shoulder 656 is provided with a shoulder 662 which defines a shoulder 664 which is received within a shoulder 666 of the side member 14. The shoulder 662 is provided with a shoulder 670 which defines a shoulder 672 which is received within a shoulder 674 of the side member 12. The shoulder 670 is provided with a shoulder 676 which defines a shoulder 678 which is received within a shoulder 680 of the side member 14. The shoulder 676 is provided with a shoulder 682 which defines a shoulder 684 which is received within a shoulder 686 of the side member 12. The shoulder 682 is provided with a shoulder 690 which defines a shoulder 692 which is received within a shoulder 694 of the side member 14. The shoulder 690 is provided with a shoulder 696 which defines a shoulder 698 which is received within a shoulder 700 of the side member 12. The shoulder 696 is provided with a shoulder 702 which defines a shoulder 704 which is received within a shoulder 706 of the side member 14. The shoulder 702 is provided with a shoulder 710 which defines a shoulder 712 which is received within a shoulder 714 of the side member 12. The shoulder 710 is provided with a shoulder 716 which defines a shoulder 718 which is received within a shoulder 720 of the side member 14. The shoulder 716 is provided with a shoulder 722 which defines a shoulder 724 which is received within a shoulder 726 of the side member 12. The shoulder 722 is provided with a shoulder 730 which defines a shoulder 732 which is received within a shoulder 734 of the side member 14. The shoulder 730 is provided with a shoulder 736 which defines a shoulder 738 which is received within a shoulder 740 of the side member 12. The shoulder 736 is provided with a shoulder 742 which defines a shoulder 744 which is received within a shoulder 746 of the side member 14. The shoulder 742 is provided with a shoulder 750 which defines a shoulder 752 which is received within a shoulder 754 of the side member 12. The shoulder 750 is provided with a shoulder 756 which defines a shoulder 758 which is received within a shoulder 760 of the side member 14. The shoulder 756 is provided with a shoulder 762 which defines a shoulder 764 which is received within a shoulder 766 of the side member 12. The shoulder 762 is provided with a shoulder 770 which defines a shoulder 772 which is received within a shoulder 774 of the side member 14. The shoulder 770 is provided with a shoulder 776 which defines a shoulder 778 which is received within a shoulder 780 of the side member 12. The shoulder 776 is provided with a shoulder 782 which defines a shoulder 784 which is received within a shoulder 786 of the side member 14. The shoulder 782 is provided with a shoulder 790 which defines a shoulder 792 which is received within a shoulder 794 of the side member 12. The shoulder 790 is provided with a shoulder 796 which defines a shoulder 798 which is received within a shoulder 800 of the side member 14. The shoulder 796 is provided with a shoulder 802 which defines a shoulder 804 which is received within a shoulder 806 of the side member 12. The shoulder 802 is provided with a shoulder 810 which defines a shoulder 812 which is received within a shoulder 814 of the side member 14. The shoulder 810 is provided with a shoulder 816 which defines a shoulder 818 which is received within a shoulder 820 of the side member 12. The shoulder 816 is provided with a shoulder 822 which defines a shoulder 824 which is received within a shoulder 826 of the side member 14. The shoulder 822 is provided with a shoulder 830 which defines a shoulder 832 which is received within a shoulder 834 of the side member 12. The shoulder 830 is provided with a shoulder 836 which defines a shoulder 838 which is received within a shoulder 840 of the side member 14. The shoulder 836 is provided with a shoulder 842 which defines a shoulder 844 which is received within a shoulder 846 of the side member 12. The shoulder 842 is provided with a shoulder 850 which defines a shoulder 852 which is received within a shoulder 854 of the side member 14. The shoulder 850 is provided with a shoulder 856 which defines a shoulder 858 which is received within a shoulder 860 of the side member 12. The shoulder 856 is provided with a shoulder 862 which defines a shoulder 864 which is received within a shoulder 866 of the side member 14. The shoulder 862 is provided with a shoulder 870 which defines a shoulder 872 which is received within a shoulder 874 of the side member 12. The shoulder 870 is provided with a shoulder 876 which defines a shoulder 878 which is received within a shoulder 880 of the side member 14. The shoulder 876 is provided with a shoulder 882 which defines a shoulder 884 which is received within a shoulder 886 of the side member 12. The shoulder 882 is provided with a shoulder 890 which defines a shoulder 892 which is received within a shoulder 894 of the side member 14. The shoulder 890 is provided with a shoulder 896 which defines a shoulder 898 which is received within a shoulder 900 of the side member 12. The shoulder 896 is provided with a shoulder 902 which defines a shoulder 904 which is received within a shoulder 906 of the side member 14. The shoulder 902 is provided with a shoulder 910 which defines a shoulder 912 which is received within a shoulder 914 of the side member 12. The shoulder 910 is provided with a shoulder 916 which defines a shoulder 918 which is received within a shoulder 920 of the side member 14. The shoulder 916 is provided with a shoulder 922 which defines a shoulder 924 which is received within a shoulder 926 of the side member 12. The shoulder 922 is provided with a shoulder 930 which defines a shoulder 932 which is received within a shoulder 934 of the side member 14. The shoulder 930 is provided with a shoulder 936 which defines a shoulder 938 which is received within a shoulder 940 of the side member 12. The shoulder 936 is provided with a shoulder 942 which defines a shoulder 944 which is received within a shoulder 946 of the side member 14. The shoulder 942 is provided with a shoulder 950 which defines a shoulder 952 which is received within a shoulder 954 of the side member 12. The shoulder 950 is provided with a shoulder 956 which defines a shoulder 958 which is received within a shoulder 960 of the side member 14. The shoulder 956 is provided with a shoulder 962 which defines a shoulder 964 which is received within a shoulder 966 of the side member 12. The shoulder 962 is provided with a shoulder 970 which defines a shoulder 972 which is received within a shoulder 974 of the side member 14. The shoulder 970 is provided with a shoulder 976 which defines a shoulder 978 which is received within a shoulder 980 of the side member 12. The shoulder 976 is provided with a shoulder 982 which defines a shoulder 984 which is received within a shoulder 986 of the side member 14. The shoulder 982 is provided with a shoulder 990 which defines a shoulder 992 which is received within a shoulder 994 of the side member 12. The shoulder 990 is provided with a shoulder 996 which defines a shoulder 998 which is received within a shoulder 1000 of the side member 14. The shoulder 996 is provided with a shoulder 1002 which defines a shoulder 1004 which is received within a shoulder 1006 of the side member 12. The shoulder 1002 is provided with a shoulder 1010 which defines a shoulder 1012 which is received within a shoulder 1014 of the side member 14. The shoulder 1010 is provided with a shoulder 1016 which defines a shoulder 1018 which is received within a shoulder 1020 of the side member 12. The shoulder 1016 is provided with a shoulder 1022 which defines a shoulder 1024 which is received within a shoulder 1026 of the side member 14. The shoulder 1022 is provided with a shoulder 1030 which defines a shoulder 1032 which is received within a shoulder 1034 of the side member 12. The shoulder 1030 is provided with a shoulder 1036 which defines a shoulder 1038 which is received within a shoulder 1040 of the side member 14. The shoulder 1036 is provided with a shoulder 1042 which defines a shoulder 1044 which is received within a shoulder 1046 of the side member 12. The shoulder 1042 is provided with a shoulder 1050 which defines a shoulder 1052 which is received within a shoulder 1054 of the side member 14. The shoulder 1050 is provided with a shoulder 1056 which defines a shoulder 1058 which is received within a shoulder 1060 of the side member 12. The shoulder 1056 is provided with a shoulder 1062 which defines a shoulder 1064 which is received within a shoulder 1066 of the side member 14. The shoulder 1062 is provided with a shoulder 1070 which defines a shoulder 1072 which is received within a shoulder 1074 of the side member 12. The shoulder 1070 is provided with a shoulder 1076 which defines a shoulder 1078 which is received within a shoulder 1080 of the side member 14. The shoulder 1076 is provided with a shoulder 1082 which defines a shoulder 1084 which is received within a shoulder 1086 of the side member 12. The shoulder 1082 is provided with a shoulder 1090 which defines a shoulder 1092 which is received within a shoulder 1094 of the side member 14. The shoulder 1090 is provided with a shoulder 1096 which defines a shoulder 1098 which is received within a shoulder 1100 of the side member 12. The shoulder 1096 is provided with a shoulder 1102 which defines a shoulder 1104 which is received within a shoulder 1106 of the side member 14. The shoulder 1102 is provided with a shoulder 1110 which defines a shoulder 1112 which is received within a shoulder 1114 of the side member 12. The shoulder 1110 is provided with a shoulder 1116 which defines a shoulder 1118 which is received within a shoulder 1120 of the side member 14. The shoulder 1116 is provided with a shoulder 1122 which defines a shoulder 1124 which is received within a shoulder 1126 of the side member 12. The shoulder 1122 is provided with a shoulder 1130 which defines a shoulder 1132 which is received within a shoulder 1134 of the side member 14. The shoulder 1130 is provided with a shoulder 1136 which defines a shoulder 1138 which is received within a shoulder 1140 of the side member 12. The shoulder 1136 is provided with a shoulder 1142 which defines a shoulder 1144 which is received within a shoulder 1146 of the side member 14. The shoulder 1142 is provided with a shoulder 1150 which defines a shoulder 1152 which is received within a shoulder 1154 of the side member 12. The shoulder 1150 is provided with a shoulder 1156 which defines a shoulder 1158 which is received within a shoulder 1160 of the side member 14. The shoulder 1156 is provided with a shoulder 1162 which defines a shoulder 1164 which is received within a shoulder 1166 of the side member 12. The shoulder 1162 is provided with a shoulder 1170 which defines a shoulder 1172 which is received within a shoulder 1174 of the side member 14. The shoulder 1170 is provided with a shoulder 1176 which defines a shoulder 1178 which is received within a shoulder 1180 of the side member 12. The shoulder 1176 is provided with a shoulder 1182 which defines a shoulder 1184 which is received within a shoulder 1186 of the side member 14. The shoulder 1182 is provided with a shoulder 1190 which defines a shoulder 1192 which is received within a shoulder 1194 of the side member 12. The shoulder 1190 is provided with a shoulder 1196 which defines a shoulder 1198 which is received within a shoulder 1200 of the side member 14. The shoulder 1196 is provided with a shoulder 1202 which defines a shoulder 1204 which is received within a shoulder 1206 of the side member 12. The shoulder 1202 is provided with a shoulder 1210 which defines a shoulder 1212 which is received within a shoulder 1214 of the side member 14. The shoulder 1210 is provided with a shoulder 1216 which defines a shoulder 1218 which is received within a shoulder 1220 of the side member 12. The shoulder 1216 is provided with a shoulder 1222 which defines a shoulder 1224 which is received within a shoulder 1226 of the side member 14. The shoulder 1222 is provided with a shoulder 1230 which defines a shoulder 1232 which is received within a shoulder 1234 of the side member 12. The shoulder 1230 is provided with a shoulder 1236 which defines a shoulder 1238 which is received within a shoulder 1240 of the side member 14. The shoulder 1236 is provided with a shoulder 1242 which defines a shoulder 1244 which is received within a shoulder 1246 of the side member 12. The shoulder 1242 is provided with a shoulder 1250 which defines a shoulder 1252 which is received within a shoulder 1254 of the side member 14. The shoulder 1250 is provided with a shoulder 1256 which defines a shoulder 1258 which is received within a shoulder 1260 of the side member 12. The shoulder 1256 is provided with a shoulder 1262 which defines a shoulder 1264 which is received within a shoulder 1266 of the side member 14. The shoulder 1262 is provided with a shoulder 1270 which defines a shoulder 1272 which is received within a shoulder 1274 of the side member 12. The shoulder 1270 is provided with a shoulder 1276 which defines a shoulder 1278 which is received within a shoulder 1280 of the side member 14. The shoulder 1276 is provided with a shoulder 1282 which defines a shoulder 1284 which is received within a shoulder 1286 of the side member 12. The shoulder 1282 is provided with a shoulder 1290 which defines a shoulder 1292 which is received within a shoulder 1294 of the side member 14. The shoulder 1290 is provided with a shoulder 1296 which defines a shoulder 1298 which is received within a shoulder 1300 of the side member 12. The shoulder 1296 is provided with a shoulder 1302 which defines a shoulder 1304 which is received within a shoulder 1306 of the side member 14. The shoulder 1302 is provided with a shoulder 1310 which defines a shoulder 1312 which is received within a shoulder 1314 of the side member 12. The shoulder 1310 is provided with a shoulder 1316 which defines a shoulder 1318 which is received within a shoulder 1320 of the side member 14. The shoulder 1316 is provided with a shoulder 1322 which defines a shoulder 1324 which is received within a shoulder 1326 of the side member 12. The shoulder 1322 is provided with a shoulder 1330 which defines a shoulder 1332 which is received within a shoulder 1334 of the side member 14. The shoulder 1330 is provided with a shoulder 1336 which defines a shoulder 1338 which is received within a shoulder 1340 of the side member 12. The shoulder 1336 is provided with a shoulder 1342 which defines a shoulder 1344 which is received within a shoulder 1346 of the side member 14. The shoulder 1342 is provided with a shoulder 1350 which defines a shoulder 1352 which is received within a shoulder 1354 of the side member 12. The shoulder 1350 is provided with a shoulder 1356 which defines a shoulder 1358 which is received within a shoulder 1360 of the side member 14. The shoulder 1356 is provided with a shoulder 1362 which defines a shoulder 1364 which is received within a shoulder 1366 of the side member 12. The shoulder 1362 is provided with a shoulder 1370 which defines a shoulder 1372 which is received within a shoulder 1374 of the side member 14. The shoulder 1370 is provided with a shoulder 1376 which defines a shoulder 1378 which is received within a shoulder 1380 of the side member 12. The shoulder 1376 is provided with a shoulder 1382 which defines a shoulder 1384 which is received within a shoulder 1386 of the side member 14. The shoulder 1382 is provided with a shoulder 1390 which defines a shoulder 1392 which is received within a shoulder 1394 of the side member 12. The shoulder 1390 is provided with a shoulder 1396 which defines a shoulder 1398 which is received within a shoulder 1400 of the side member 14. The shoulder 1396 is provided with a shoulder 1402 which defines a shoulder 1404 which is received within a shoulder 1406 of the side member 12. The shoulder 1402 is provided with a shoulder 1410 which defines a shoulder 1412 which is received within a shoulder 1414 of the side member 14. The shoulder 1410 is provided with a shoulder 1416 which defines a shoulder 1418 which is received within a shoulder 1420 of the side member 12. The shoulder 1416 is provided with a shoulder 1422 which defines a shoulder 1424 which is received within a shoulder 1426 of the side member 14. The shoulder 1422 is provided with a shoulder 1430 which defines a shoulder 1432 which is received within a shoulder 1434 of the side member 12. The shoulder 1430 is provided with a shoulder 1436 which defines a shoulder 1438 which is received within a shoulder 1440 of the side member 14. The shoulder 1436 is provided with a shoulder 1442 which defines a shoulder 1444 which is received within a shoulder 1446 of the side member 12. The shoulder 1442 is provided with a shoulder 1450 which defines a shoulder 1452 which is received within a shoulder 1454 of the side member 14. The shoulder 1450 is provided with a shoulder 1456 which defines a shoulder 1458 which is received within a shoulder 1460 of the side member 12. The shoulder 1456 is provided with a shoulder 1462 which defines a shoulder 1464 which is received within a shoulder 1466 of the side member 14. The shoulder 1462 is provided with a shoulder 1470 which defines a shoulder 1472 which is received within a shoulder 1474 of the side member 12

position illustrated in FIG. 2. Thus as will be appreciated, the reel 38 can be manually rotated by crank 44 to wind the tape blade 20 onto drum 46 for storage within compartment 16.

In accordance with the present invention the reel member 38 is also provided with an axially slotted or segmented reel hub or central shaft 60 that extends toward the conical center post 32. As shown in FIGS. 2 and 3, the shaft 60 is comprised of three equally spaced leg portions 62 having arcuately tapered free end surfaces 64 for contacting the conical nose 34 of center post 32. The legs 62 are of a slightly greater length than the distance required to assure contact with the center post so that forced engagement of the surfaces 64 with the conical nose 34 tends to spread the legs 62 outwardly. Simultaneously this causes an axial force on the reel member 38 urging the peripheral flange 40 into intimate frictional engagement with the radially projecting lip 30 of the casing. This constant frictional engaging force between the central shaft of the reel member and the center post of the casing prevents free-wheeling of the reel member 38 and permits the application of a smooth torque force to the reel as the blade is retracted into the storage compartment of the casing.

The reel 38 may be constructed of suitably sturdy yet flexible material capable of providing the desired frictional properties, strength, memory and durability, particularly in the leg portions 62 of the reel shaft. In this connection it has been found that acetal resins, such as the material sold under the name "Delrin" by E. I. du Pont & Co., provide the desired properties.

The side members 12, 14 are each provided with a plurality of snap-fit connections that facilitate initial assembly of the casing members 12, 14 and assure application of an axial force on the reel member 38. As shown in FIG. 2, these snap-fit connections can take the form of segmented plastic snaps 68 and clasps 70 located in alignment adjacent the periphery of the casing at spaced locations and capable of holding the side members together until they are permanently fastened by ultrasonic welding, threaded fasteners or the like. In the particular embodiment illustrated, three such snap-fit connections cooperatively interengage to provide the desired retention of the side members in their aligned mated position.

As mentioned, it is also a feature of the present invention that the casing need not be reopened or disassembled in order to replace a worn or damaged rule blade. This is achieved by utilizing a rule blade 20 having a suitable replacement blade attaching means adjacent the interior or butt end thereof but spaced therefrom sufficiently to permit exposure outside the blade casing when the blade is fully extended. In the particular embodiment illustrated in FIGS. 1 and 4, the replacement blade attaching means takes the form of a triangular aperture 72 located centrally across the face of blade 20.

The blade 20 is also provided with a laterally weakened break away area to permit complete removal of the printed portion of the original blade prior to replacement. As will be appreciated most blade damage and wear occurs on that portion of the blade capable of being exposed and primarily upon the forwardmost end thereof. Thus a break away area can be incorporated in front of aperture 72 by providing a pair of laterally aligned edge notches 74. The exposed printed

portion of the original blade 20 then can be easily and rapidly detached from its integral trailing leader portion at the weakened area and a replacement blade can be quickly attached at the replacement blade attaching aperture 72.

The forwardmost end of the tape blade 20 is also provided with a hook unit 76 that facilitates its withdrawal from the case. The hook unit 76 illustrated in FIG. 1 is of the folding type so that it can be conveniently and neatly received within a casing recess 78 located adjacent the aperture 18.

As can be seen from the foregoing detailed description the present invention provides a simplified and economical crank operated long tape that avoids free-wheeling of the reel member. This is accomplished by providing a segmented reel shaft that constantly bears against a conical center post on the interior of the casing to provide both centering of the reel and stabilized frictional engagement between the reel and the casing. Additionally the structure of the present invention need not be disassembled for replacement of a broken or damaged blade since the original blade can be snapped off at a weakened area near its butt end leaving a leader to which a replacement blade can be easily secured. Additionally the assembly of the unit is facilitated by a plurality of spaced snap-fit interlocking elements that can be molded into each of the casing side members to hold the assembly together until more permanent securing means are installed.

As will be appreciated by persons skilled in the art, various modifications, adaptations and variations of the foregoing specific disclosure can be made without departing from the teachings of the present invention.

I claim:

1. In a tape measure, the combination comprising a casing, having a lip portion a reel member mounted on the casing for rotary motion relative thereto, a relatively long tape wound within the casing and having one end extending from said casing, a center post within the casing, said reel member having a central shaft extending coaxially toward the center post for engagement therewith and a rim radially spaced from the shaft for engagement with the lip portion of the casing, one of said central shaft and said center post being segmented to define a plurality of leg portions having free ends and the other of said shaft and post having a cam surface, said free ends bearing against said cam surface to urge said leg portions apart and thus provide an axial thrust to the reel within the casing and simultaneously provide constant frictional engagement between the rim of the reel member and the lip of the casing for resisting said axial thrust and rotary movement of the reel member with respect to the casing.

2. The tape measure of claim 1 wherein said central shaft is axially segmented and the center post is tapered to bias the free ends of the leg portions outwardly during assembly.

3. The tape measure of claim 1 wherein the casing comprises a pair of mating casing members having opposed side walls and an opening for a tape to pass through, said center post extending integrally from one of said opposed side walls and having a conical free end engaging said leg portions.

4. The tape measure of claim 1 wherein said casing has a side wall with an enlarged central aperture defined by said lip portion, said reel member being mounted within said central aperture and including a

wind-up drum and a peripheral flange provided with said rim for engaging said lip to prevent removal of the reel member from the casing, said long tape being wound on said wind-up drum and having one end secured thereto.

5. The tape measure of claim 1 wherein said long tape has a butt end secured to the reel and is provided with a laterally weakened break area adjacent said butt end and a replacement tape attaching means intermediate said break area and said butt end, both said break area and said attaching means being spaced from said butt end by a distance sufficient to permit full exposure thereof outside the casing without disengagement from the reel.

6. The tape measure of claim 5 wherein the laterally weakened area includes side notches in the tape blade and the attaching means includes an aperture in the tape blade.

7. The tape measure of claim 1 wherein said segmented shaft is constructed of acetal resin.

8. The tape measure of claim 1 including a crank arm mounted on the reel through a snap fit pivot connection.

9. In a tape measure, the combination comprising a pair of mating casing members having opposed side walls and an opening for a tape to pass through, one of said opposed side walls having an inwardly projecting center post and the other of said side walls having an enlarged central aperture defined by a peripheral circular lip, said center post having a tapered cam surface, 30

a reel member mounted within the casing and projecting through said central aperture, said reel member including a wind-up drum and a peripheral flange having a rim engaging said circular lip to prevent removal of the reel member from the casing, a relatively long tape wound on said drum and having one end secured to said drum and its opposite end extending from said casing opening, crank means mounted on said reel member for winding an extended portion of the tape into 10 said casing and onto said drum, said reel member having a central shaft extending toward the center post for engagement therewith, said central shaft being axially segmented to define a plurality of leg portions having free ends bearing against the tapered cam surface of said center post to provide axial thrust to the reel within the casing and simultaneously provide constant frictional engagement between the rim of the reel member and the lip of the casing for resisting said axial thrust and rotary movement of the reel member with respect to the casing.

10. The tape measure of claim 9 wherein said center post has a tapered end engaged by the leg portions of the central shaft, said leg portions being equally spaced.

11. The tape measure of claim 9 wherein the drum is provided with a key-hole slot and the end of the tape secured to the drum is provided with a T-shaped end portion.
